UNITED STATES PATENT OFFICE.

JOHN B. FEATHER, OF ROARING SPRING, PENNSYLVANIA.

SLIDING WINDOW-SCREEN.

SPECIFICATION forming part of Letters Patent No. 694,095, dated February 25, 1902.

Application filed October 14, 1901. Serial No. 78,614. (No model.)

To all whom it may concern:

Be it known that I, JOHN B. FEATHER, a citizen of the United States, residing at Roaring Spring, in the county of Blair, State of Pennsylvania, have invented certain new and useful Improvements in Sliding Window-Screens; and I do hereby declare the following to be a full, clear, and exact description of the invention, such as will enable others skilled in the art to which it appertains to make and use the same.

This invention relates to window-screens in general, and more particularly to the mountings thereof; and it has for its object to provide a cheap, simple, and efficient arrangement whereby a window-screen may be held slidably in position without the use of the usual beads or strips.

A further object of the invention is to provide a construction which will permit of easy application and removal of the screen and which, furthermore, will prevent the bottom of the frame from striking the sill with the usual violent blow, other objects and advantages of the invention being understood from the following description.

In the drawings forming a portion of this specification, and in which like numerals of reference indicate similar parts in the several views, Figure 1 is an elevation showing the screen in place in a window-frame. Fig. 2 is a view showing one of the screw-eyes and the guide-rod and illustrating the manner in which the eye is engaged with the rod after the screen has been applied or removed. Fig. 3 is a top plan view of one of the rods and showing one of the screw-eyes with which it is engaged. Fig. 4 is a transverse section of the upper sides of a window-sash and screen-frame with the flange on the latter.

Referring now to the drawings, there is shown a window-frame including the sides 5 and 6, the sill 7, and the top 8, and against the inner faces of the sides of the frame are secured the two guide-rods 9 and 10. Each of the guide-rods 9 and 10 consists of an upper straight portion and a lower flattened foot 11, which is offset with respect to the upper portion of the rod and is parallel therewith, the foot being connected with the upper portion of the rod by means of the diagonal or inclined portion 12. The foot of each rod has

a single perforation therein, and engaged with this perforation is a screw 13, which is screwed into the face of the frame, so that the rod is held securely against movement transversely of the window, but yet may be swung with its upper end away from the window-frame.

The screen-frame 15, as shown, is provided with screw-eyes 16 and 17, engaged with its sides, and in placing the screen the upper ends of the rods are swung into the room and the rods are then threaded through the screw-eyes on the screen-frame, after which the rods are returned to their vertical positions to hold the screen close against the bead 18, disposed between the window-sash and the screen-frame. By forcing the upper ends of the rods inwardly the screen-frame is pressed against the beads. To hold the upper ends of the rods against outward movement, the screw-eyes 20 and 21 are provided, and each screw-eye includes a head and a threaded stem, as usual; but in the present instance the head extends at one side farther from the continuation of the axis of the stem than it does at the opposite side. The screw-eyes are engaged with the inner faces of the sides of the frame near to the upper ends of the rods, and by turning the heads to vertical positions and moving the rods against the lower sides of the heads the upper ends of the rods will extend slightly above the continuations of the axes of the stems, and by then turning the heads into horizontal positions they will be caused to take over the upper ends of the rods and hold them against rearward movement, the rods being then held by the inner faces of the outer sides of the heads. As the sides of the heads are of different lateral extensions, by reversing the heads the pressure thereof against the rods will be changed and the pressure of the rods against the screen to hold it against the beads will be changed, it being understood that the rods are of spring metal, so that they may be placed under tension. Thus by reversing the screws the tensions of the rods may be adjusted.

When the screen is to be removed, all that is necessary is to turn the upper screw-eyes 20 and 21, and the rods may be then moved outwardly at their upper ends and the screen removed therefrom.

When the screen is lowered, the lower eyes

engaged with the frame thereof strike upon the diagonal portions of the rods with a wedging action to ease the lower terminal movement of the screen-frame, so that while the 5 bottom of the frame finally strikes the sill it does so without a hard knock.

The space between the upper side of the screen-frame and the upper rail of the window-sash is bridged by a strip 24, secured to 10 the upper side of the screen-frame and extending in the direction of the window-sash.

In practice modifications of the specific construction shown may be made and any 15 suitable materials and proportions may be used for the various parts without departing from the spirit of the invention.

What is claimed is—

1. The combination with a window-frame, of guide-rods having diagonal portions and 20 adjacent lower laterally-offset feet pivotally connected to the inner faces of the frame, screw-eyes engaged with the inner faces of the frame and in position for rotation into engagement over the ends of the rods, and a 25 window-screen disposed behind the rods and having eyes engaged therewith and disposed to strike the diagonal portions of the rods to ease the lower terminal movement of the screen.

30 2. The combination with a window-frame, of guide-rods having laterally-offset feet at their lower ends pivotally connected to the

inner side faces of the frame, the feet being connected with the upper portions of the rods by diagonal portions, screw-eyes engaged with 35 the inner side faces of the frame and in position for rotation into engagement with the upper ends of the rods, said eyes having the sides of their heads projected to different extents beyond the continuations of the axes of 40 the stems thereof, a screen disposed behind the rods, and eyes carried by the frame and engaged with the rods and adapted to strike the diagonal portions when the screen is lowered. 45

3. The combination with a window-frame, of guide-rods having laterally-offset feet at their lower ends pivotally connected to the inner side faces of the frame, screw-eyes engaged with the inner side faces of the frame 50 and in position for rotation into engagement with the upper ends of the rods, said eyes having the sides of their heads projected to different extents beyond the continuations of the axes of the stems thereof, a screen disposed 55 behind the rods, and eyes carried by the frame and slidably engaged with the rods.

In testimony whereof I affix my signature in presence of two witnesses.

JOHN B. FEATHER.
